UNITED STATES PATENT OFFICE.

AUGUSTUS C. DURDIN, JR., OF CHICAGO, ILLINOIS, ASSIGNOR TO CHICAGO PUMP COMPANY, OF CHICAGO, ILLINOIS, A CORPORATION OF ILLINOIS.

CENTRIFUGAL PUMP.

Application filed February 7, 1927. Serial No. 186,390.

This invention relates to centrifugal pumps and more particularly to the impellers thereof, and its principal object is to simplify and otherwise improve upon the construction upon such parts of centrifugal pumps. The invention concerns centrifugal pumps of the type used for ejecting sewage or drainage water, or for ejecting liquids which contain hard substances, trash, litter, blocks of wood, stone, semisolid materials and so forth, which cannot be handled by the ordinary centrifugal pump because of the danger of injury to the parts thereof and because of the danger of the pump becoming clogged. Another object of the present invention is to increase the capacity of centrifugal pumps of this type and to reduce to a minimum the formation of eddies in the volute part of the pump, which are of common occurrence and interfere with the efficient operation of the pumps. Another object is to provide a centrifugal pump impeller which may be cast in one piece and which does not require the use of complicated sand cores in the casting thereof.

With these ends in view, this invention consists in a centrifugal pump impeller having a vane or vanes of substantially uniform thickness and cross section throughout their length, and each having a rounded, relatively wide forward end and formed with a reentrant part behind the rounded forward end, whereby articles, having a greater length (within given limits) than the diameter of the eye of the impeller, may freely pass through the impeller and be ejected from the pump. The invention further consists in the several novel features hereinafter fully set forth and claimed.

The invention is clearly illustrated in the accompanying drawing, in which:

Fig. 1 is a front elevation of a centrifugal pump impeller embodying a simple form of the present invention; Fig. 2 is a vertical section thereof taken on a plane parallel with the front of the impeller seen in Fig. 1; Fig. 3 is a cross section taken on the line 3—3 of Fig. 1 and Fig. 4 is a cross section taken on the line 4—4 of Fig. 1.

Referring to said drawing, which illustrates a simple embodiment of the present invention, the reference character 5 designates a vane supporting member, here shown in the form of a circular wall or plate, having on one side a hub 6 in which is secured the drive shaft of the pump. Spaced from the wall 5 is a circular wall 7, which is parallel therewith and contains a centrally located circular opening 8, which forms the eye of the impeller, through which the pumped material enters the same. Secured to said walls 5, 7, and as a preference cast integrally therewith are the vanes 9 of the impeller. Two vanes are shown in the drawings, but the number of vanes is immaterial to this invention, broadly considered, as a lesser or greater number may be used. Each vane is of substantially uniform thickness and cross section throughout its entire length, although at the sides thereof where it joins the walls 5, 7, fillets 10 are formed between the vane and walls, which fillets increase the thickness somewhat at these places, but add strength and rigidity to the whole structure and prevent the gathering of trash and other material in the corners between the vanes and walls.

Each vane is given a form somewhat in the nature of a volute or spiral, commencing at the forward end with a rounded part 11, which is preferably semicircular in form and extends from a point adjacent, but outside of the eye 8 of the impeller to a point well within the margin or periphery of the walls 5, 7. From the semicircular forward end 11, each vane extends in a curvilinear manner, as at 12 toward the peripheries of the walls 5, 7, where the part 13 of the outer face of the vane is made concentric with the axis of the impeller and coincides with the peripheries of the walls. Said part 13 extends along the periphery of the impeller for a considerable distance, in fact good results are obtained with the vane extending along the periphery of the impeller through an arc of sixty degrees or thereabouts. At the rear or discharge end 14 the edge portion of each vane may thin out to a relatively sharp edge if desired, the inner face of each vane being beveled or curved outward toward the outer side as shown in Fig. 2.

It will be observed that the curved forward ends 11 of the vanes are relatively wide, and being of arch like formation they effectively prevent the collection of rags, paper and other like articles on the front of the impeller vanes, which would otherwise gather thereon if the front of the impeller vanes were relatively thin. Furthermore

by making said forward ends of widely curved or arch like formation they are capable of withstanding shocks and jars caused by the impact of hard bodies on the ends of the vanes. Behind the curved forward ends of each vane is a reentrant portion 15, which affords a wide space considerably wider than the diameter of the eye of the impeller, thereby permitting objects, which are longer (within given limits) than the diameter of the eye of the impeller, to freely pass through the space between the vanes. Sticks, blocks of wood, stones and so forth which are relatively long as compared with their diameter are not likely to be caught between the vanes but may pass on through the impeller thereby avoiding the clogging of the pump.

It will be understood to those skilled in the art to which this invention pertains, that a pump case encloses the impeller and as usual said case takes a volute form around the impeller. Because of the parallel relation of the inner and outer faces of the vanes, and because a large part of the rear ends of said vanes are concentric with the axis of rotation of the impeller, the water in traveling through the pump may substantially follow said parallel lines, so that as the bodies of water on both sides of each vane come together at the rear end of each vane, but little disturbance is created between the meeting bodies of water, since they are flowing substantially in the same direction. The result is that practically no eddies are created and the efficiency of the pump is thereby greatly increased. The curvature given to the vanes is suitable for the purpose of impelling the water, together with the foreign substances contained therein, through the pump and of transmitting thereto, force applied to the pump, thereby increasing the velocity of the water. Furthermore by reason of the shape and disposition of the vanes, the entire impeller may be cast in one piece without any core pockets in the vanes, from which the sand cores must be removed. The impeller is of a form which may be easily machined, is light, substantial and strong, and capable of long continued usage.

More or less variation of the exact details of construction is possible without departing from the spirit of this invention. I desire, therefore, not to limit myself to the exact form of the construction shown and described, but intend, in the following claims, to point out all of the invention disclosed herein.

60 I claim as new, and desire to secure by Letters Patent:

1. In a centrifugal pump impeller, a vane of uniform thickness throughout, formed at its forward end with a U bend to provide a rounded and relatively wide impact end,

the remainder of the vane beyond the U bend extending in a curvilinear manner from a point within and spaced away from the circumference of the impeller to one on its periphery, and thence part way along the 70 periphery on a concentric path.

2. In a centrifugal pump impeller, a vane of uniform thickness throughout, formed at its forward end with a U bend to provide a rounded and relatively wide impact end, the remainder of the vane beyond the U bend extending in a curvilinear manner from a point within and spaced away from the circumference of the impeller to one on its periphery and thence extending part way in 80 a concentric path, along its periphery to its rear end.

3. In a centrifugal pump impeller, the combination of a pair of parallel, circular vane supporting walls, and a vane extending from wall to wall, said vane being of uniform thickness throughout and formed at its forward end with a U bend to provide a rounded and relatively wide impact end, the remainder of said vane extending in a curvilinear manner from a point within and spaced away from the circumference of the impeller to one on its periphery, and thence part way along the periphery in a concentric 90 path.

4. In a centrifugal pump impeller, the combination of a pair of parallel, circular vane supporting walls, and a vane extending from wall to wall, said vane being of uniform thickness throughout and formed at its forward end with a U bend to provide a rounded and relatively wide impact end, the remainder of said vane extending in a curvilinear manner from a point within and spaced away from the circumference of the impeller to one on its periphery and thence extending part way in a concentric path along its periphery to its rear end.

5. In a centrifugal pump impeller, a vane of uniform thickness throughout and provided with a convexly rounded forward end, the vane extending in a curvilinear manner from a point within and spaced away from the circumference of the impeller to one on its periphery, and thence part way along the periphery on a concentric path.

6. In a centrifugal pump impeller, a vane of uniform thickness throughout and provided with a convexly rounded forward end, the vane extending in a curvilinear manner from a point within and spaced away from the circumference of the impeller to one on its periphery and thence extending in a concentric manner along the periphery of the impeller to its rear end, there being a reentrant portion on the inner side of the vane behind said convexly rounded forward end.

7. In a centrifugal pump impeller, a vane provided with a convexly rounded forward part located within and spaced away from 120

the periphery of the impeller, and having a part of uniform thickness, extending from said convexly rounded forward part to the periphery of the impeller in a curvilinear manner, and thence part way along the periphery on a concentric path.

8. In a centrifugal pump impeller, a vane provided with a convexly rounded forward part located within and spaced away from the periphery of the impeller, and having a part of uniform thickness, extending from said convexly rounded forward part to the periphery of the impeller in a curvilinear manner and thence in a concentric manner to its rear end.

9. In a centrifugal pump impeller, the combination of a circular vane supporting wall and a vane supported thereby and provided with a convexly rounded forward part

and having a part located within and spaced away from the periphery of the impeller of uniform thickness, extending from said convexly rounded forward part to the periphery of the impeller in a curvilinear manner, and thence part way along the periphery on a concentric path.

10. In a centrifugal pump impeller, the combination of a circular vane supporting wall and a pair of vanes supported by said wall and each provided with a convexly forward part and having a part located within and spaced away from the periphery of the impeller of uniform thickness extending from said convexly rounded forward part to the periphery of the impeller in a curvilinear manner and thence in a concentric manner along the periphery of the impeller.

AUGUSTUS C. DURDIN, JR.
